UNITED STATES PATENT OFFICE.

HENRY T. CREPEAU, OF HAVERHILL, MASSACHUSETTS, ASSIGNOR TO FREDERICK C. BOYD, OF BRIDGEPORT, CONNECTICUT.

AUTOMATIC VENDING-MACHINE.

SPECIFICATION forming part of Letters Patent No. 417,354, dated December 17, 1889.

Application filed July 17, 1889. Serial No. 317,761. (No model.)

To all whom it may concern:

Be it known that I, HENRY T. CREPEAU, a citizen of the United States, residing at Haverhill, in the county of Essex and State of Massachusetts, have invented certain new and useful Improvements in Automatic Vending-Machines; and I do hereby declare the following to be a full, clear, and exact description of the invention, such as will enable others skilled in the art to which it appertains to make and use the same.

My invention relates to certain new and useful improvements in machines for automatically selling merchandise of various kinds; but it is particularly adapted for the sale of cigars or articles put up in small packages, such as cigarettes or confections.

The objects of my invention are to furnish a machine which shall be simple in construction and cheap to manufacture, which shall discriminate between the coin for which it is adapted and coins of other denominations, in which the operating mechanism shall be screened from view, and in which the opening of the top of the case for the insertion of a fresh supply of goods will not admit of the inspection or operation of the device by which the drawer is released.

With these ends in view my invention consists in the coin-operated device whereby the drawer is released, in the arrangement of the chute and the means whereby it is connected with the slots at the front of the case for the introduction of the coin, in the locking of the partition so that it can be withdrawn only by one having access both to the top of the machine and to the money-drawer, and, generally, in the details of construction and combination of elements hereinafter fully explained, and then recited in the claims.

In order that those skilled in the art to which my invention appertains may fully understand its construction and method of operation, I will describe the same in detail, reference being had to the accompanying drawings, which form a part of this specification, and in which—

Figure 1 is a perspective of a machine constructed in accordance with my invention, said machine being adapted to contain two qualities of cigars; Fig. 2, a central vertical section

through one of the sides whereof the other is a duplicate; Fig. 3, a detail plan view of the drawer and the locking mechanism therefor; Fig. 4, a detail vertical section through the drawer, showing the latch in its disengaged position; Fig. 5, a detail vertical section showing in full lines the cover partially raised, so that the slot and chute are disconnected, and in dotted lines the position of the cover and block when turned entirely back; Fig. 6, a detail transverse vertical section showing the means for locking the partitions.

Like numerals denote the same parts in all the figures of the drawings.

1 is the case, which is provided with a hinged and locked cover 2 at its top, and with a locked money-receptacle, as a drawer 3, beneath. The front of the case has a glass plate or plates 4, according as the machine is adapted for one or more kinds or qualities of goods. Behind the glass front and at a distance therefrom sufficient to accommodate the goods is a partition 5, preferably of wood, which forms a backing against which the goods rest, and which also prevents inspection of the working parts of the machine. The partition is arranged in ways, (see Fig. 6,) and when moved is drawn upward through the top of the case. For the purpose herein-after explained, however, it is normally held as against such withdrawal by a tongue 6, which extends through a slot into the money-drawer and is held by a pin 7 or other suitable fastening device, which passes through it.

8 is a chute supported in brackets 9 within the case at the rear of the slide just described, the upper end of said chute resting close to said slide, which from thence to its top is slotted, as seen at Figs. 2 and 5.

Hinged upon the cover 2 is a block 10, of a size just sufficient to fill the space between the front of the case and the slide. (See Figs. 2 and 5.) Said block has a slot 11 passing obliquely through it, which slot, when the block is in its closed position, as at Fig. 2, connects the upper end of the chute 8 with the opening 12 at the front of the machine, in which the coin is adapted to be deposited. The object in using this block is to admit of the locking devices and chute being placed at the rear of the case and of a connection

between the chute and slot, while at the same time the cigars or other merchandise may, by raising the block, be inserted through the hinged cover at the top.

5 13 is a drawer arranged in the case between the money-drawer and the lower end of the slide 5. Near its front end, and immediately beneath the space in which the goods are piled, this drawer has a transverse recess 14, 10 in which the lowermost article normally rests, and in the construction of the drawer the height from the bottom of the recess to the top of the front of the drawer is slightly greater than the thickness of one of the articles to be sold. Just behind the recess just referred to is a locking-aperture 15, cut through or partially through the drawer, and at the rear of this aperture the drawer is cut away toward its rear end. (See Figs. 2 and 4.) 15 20 16 is a stop secured to the bottom of the drawer and running in a slot in the partition beneath it, whereby the outward movement of the drawer is limited.

17 is a spring secured to the drawer and to 25 some fixed point in the case, whereby said drawer is returned to its closed position after it has been pulled out and released.

18 is a bifurcated bracket secured to the case slightly above the line of the drawer, 30 and between its outer ends is pivoted a lever 19, having at its forward end a downwardly-projecting hook 20, adapted to engage the locking-aperture in the drawer, and at its rear end a pan or plate 21, whose rear extremity is slightly contracted in width and extends between two vertical projections or posts 22 on the bracket. (See Figs. 3 and 4.) 35 The lower end of the chute terminates directly above the pan and slightly in front of the posts. The lever is so pivoted as to be slightly overbalanced at the hook end, which is normally engaged with the locking-aperture in the drawer when the latter is closed.

40 The money-receptacle, as is seen at Figs. 2, 3, 45 and 4, is open relative to the goods-drawer at its rear end to receive the coins as they are deposited.

45 The operation of my invention is as follows: The machine is filled with the merchandise—such as cigars or the like—to be sold by raising the hinged cover and inserting the goods between the glass front and the partition, the blocks being of course raised with the cover, so as to leave the merchandise-space entirely 50 open. The cover is then closed and locked, the blocks returning to the position shown at Fig. 2, so as to connect the coin-slot with the chute. When the proper coin is inserted, it passes down the chute and lands upon the pan 55 at the rear end of the locking-lever, thereby overbalancing the hook and lifting it out of the locking-aperture in the drawer. The coin is retained upon the pan by its engagement with the two vertical posts upon the bracket, 60 which are so close together as to preclude the passage of the coin between them. A coin smaller than that for which the machine is

adapted will pass between the posts into the money-receptacle beneath without operating the lever. If a coin of the proper size be used, but which is lighter than the coin for which the machine is designed, it will fail to raise the lever and release the drawer. A coin of excessive size cannot be inserted through the slot at the front of the machine. 70 When the hook has been lifted out of the locking-aperture by a proper coin, the drawer may be freely opened and the lowermost cigar which rests in the recess be removed by the purchaser. As the drawer moves outward, 75 the support for the coin theretofore furnished by its edge resting against the vertical posts is removed, and it slides from the pan into the money-receptacle beneath. When the drawer is released, it is carried back to its 80 closed position by the spring, the pile of cigars falls one space, so that the lowermost one of the pile is in the recess in the drawer, and the hook engages by gravity with the locking-aperture. 85 90

As these machines might be left in charge of some person whose duty it would be to replenish the stock from time to time, but to whom it was undesirable to intrust the key of the money-receptacle, or to give access to 95 the working parts, the partition is arranged to be held in place by the locking device, which is accessible only from the money-receptacle, as heretofore set forth.

I claim—

1. In an automatic vending-machine, the combination, with the case and the goods-drawer arranged to slide therein, and the locking devices for the latter, of the movable partition and the locking-tongue projecting downward into the money-receptacle, the chute extending from the locking devices upward to a point near the top of the partition, and the movable block provided with a slot and adapted to connect the slotted case-front 100 with the chute, substantially as set forth.

2. In a machine of the character described, the combination, with the case, the goods-drawer and the money-drawer, of the partition arranged and adapted to slide vertically 115 in ways parallel with the front of the case, the downwardly-extended tongue projecting into the money-drawer, and a fastening device whereby the withdrawal of the slide is prevented, substantially as specified.

3. In an automatic vending-machine, the combination, with the drawer having a goods-recess and a locking-aperture, of a bracket secured in the case above the drawer, a hooked and overbalanced lever pivoted to the bracket 125 and engaging the drawer, as described, said bracket provided with posts at the rear of the lever, whereby the edge of the coin is engaged, and the chute terminating directly over the rear end of the lever and in front of 130 the posts, substantially as described.

4. In an automatic vending-machine, the combination, with the case, of the cash-drawer, the goods-drawer having a locking-aperture

- and goods-recess, the bracket having the over-balanced hook-ended locking-lever pivoted thereto, the chute extending from the top of the partition to the lighter end of the locking-lever, the slotted block hinged to the cover and adapted to connect the chute with the slotted front of the case, the sliding partition forming a back for the goods-receptacle, and a suitable locking device connected to the partition and accessible only from the money-drawer, whereby said partition is held as against withdrawal from the top of the case, all arranged as described, and for the purpose specified.
- 5 5. In an automatic vending-machine, the combination, with the goods-receptacle, the goods-drawer, the locking devices, and the chute, of the cover and the slotted block hinged thereto, said block adapted to slide into or out of the top of the goods-receptacle, substantially as set forth.
- 10 6. The combination, with the case, the chute, the drawer, and the locking mechanism, of the slot at the front of the case for the introduction of the coin, the cover for the closing of the top of the case, and the block

having therethrough oblique slot, said block hinged to the cover and adapted thereby to be raised and lowered relative to the chute and coin-slot, as set forth.

30

7. In an automatic vending-machine, the combination, with the case, of the removable partition arranged therein and forming a backing for the goods-receptacle, and a lock connected with said partition and extending into the money-receptacle, substantially as specified.

35

8. In an automatic vending-machine, the combination, with the drawer having a recess and also a locking-aperture, of the pivoted locking-lever secured to the rear of the case, the chute extending from the front of the case to the rear of the locking-lever, and a stop arranged at the rear of the hook, whereby the coin is detained until the drawer is opened, substantially as specified.

40

In testimony whereof I affix my signature in presence of two witnesses.

HENRY T. CREPEAU.
